UNITED STATES PATENT OFFICE.

HENRY M. CROUSE, OF CHICAGO, ILLINOIS, AND GEORGE G. NEWELL, OF NEWAYGO,
MICHIGAN.

AUTOGRAPHIC REGISTER.

Original application filed June 24, 1918, Serial No. 241,629. Divided and this application filed October
14, 1920. Serial No. 416,906.

This invention relates to autographic roller registers, and more particularly to the paper feeding mechanism for such registers, this application being a division of application Serial No. 241,629, filed June 24, 1918, which eventuated into Patent No. 1,355,816.

One of the objects of the invention is to automatically throw out of operative position the auxiliary parts of an autographic register, such as the strip printing mechanism and the supplementary feed therefor, when the paper feeding mechanism is thrown out of proper adjustment.

15 Further objects of the invention will appear from the following specification taken in connection with the drawings in which—

Figure 1 is a vertical longitudinal section of the autographic register;

20 Figure 2 is a detail sectional view showing the clutch mechanism for the auxiliary paper feeding means used in connection with the printing rollers;

Figure 3 is a detail sectional view showing the driving connections between the paper feeding rollers; and

25 Figure 4 is a detail view in elevation showing the cover plate for the register.

The register employed is provided with a casing made up of two sections, a front section 20 and a rear section 21. The front section houses the paper supply reels 21' which are supported as shown, one above the other. The paper after leaving the supply rollers passes between suitable type rollers 22 and compression rollers 23, the latter being pressed toward the type rollers by means of springs 24. The type rollers 22 contact with inking rollers 25 disposed below the same and print upon the record strips the desired data for receiving the record in the register. The paper strips after passing through the printing mechanism are led around an idler 26 and across the platen 27 suitably supported between the side walls of the casing 21, and from the platen the strips pass between the paper feeding rollers 28. These rollers are actuated from a shaft 29 by means of a gear 30 which meshes with a gear 31 carried by the lower feed roller at one end thereof. At its opposite end the lower roller carries a gear 31' which meshes with a corresponding gear 32 carried by the upper feed

55 prevent the reverse rotation of the driving gear 30. We prefer to construct the driving mechanism in such a manner that the throw of the handle 34 carried by the shaft 29 through 180° will feed one strip of paper. 60

The construction above described is fully shown and described in Patent No. 1,254-988, issued January 29, 1918, and for this reason a more complete showing of this construction is believed to be unnecessary 65 in this application.

Suitable knives 35 are provided in rear of the feeding rollers for the purpose of severing the records retained in the machine, these records passing downwardly 70 through a chute 36 and being fed into the bottom of the casing by means of a roller 37 which is provided with a gear 38 meshing with the gear 30 carried by the feed shaft 29. 75

The type rollers 22 are positively rotated, and driving connections between these rollers and the driving gear 30 are provided, these connections including means for disconnecting the type rollers from their operating mechanism when the feeding rollers of the register are thrown out of proper feeding adjustment. The type rollers 22 in conjunction with the pressure rollers 23 constitute supplemental paper 80 feeding means or mechanism.

Referring now to Figures 1 and 2, a gear 39 is carried by a sleeve 40 slidably mounted on a shaft 41 suitably supported between the walls of the autographic register, and 85 this gear 39 meshes with an idler gear 39' carried by a suitably supported shaft 40', which in turn engages the driving gear 30 carried by the shaft 29. The sleeve 40 adjacent the gear 39 is provided with clutch 90 teeth 42 adapted to mesh with corresponding clutch teeth 43 formed integral with or suitably secured to a sprocket wheel 44, also carried by the shaft 41. The sleeve 40 is provided near one end with fixed spaced 100 apart collars 45 between which is carried a bifurcated clutch shipping fork 46 secured to an angular bracket 47. The bracket 47 is carried at the upper end of a spindle 48 carried by a bracket 48' and which is provided at its lower end with a laterally projecting arm 49 pivotally connected with a slide bar 50 slidably carried by brackets 105

51 secured to one side wall of the autographic register. The slide bar 50 is normally spring pressed in a rearward direction by means of a spring 52 which contacts at 5 one end with a pin 53 carried by the slide bar 50, and at the opposite end with one of the brackets 51 carried by the side wall of the register. The rear wall 54 of the autographic register is hinged at 55 to the bottom wall of the rear casing 21, the rear wall 54 being provided with suitable locking means comprising a key actuated bolt 56 which cooperates with members 57 carried by a bridge plate 58 connected with the side 10 walls of the register, whereby the rear hinged wall 54 may be locked in closed position.

From the above description it will be seen that as the rear wall is swung rearwardly 20 and downwardly the spring 52 will force the slide bar 50 rearwardly, actuating the clutch shipping fork 46 to throw the clutch members 42 and 43 out of mesh with each other, thereby disconnecting the sprocket 25 wheel 44 from the driving gear 39. The sprocket wheel 44 is connected by a chain 59 to corresponding sprocket wheels carried by the type rolls, these rolls being driven simultaneously.

30 As illustrated, the upper feed roller is carried by the cover plate 60 hinged at 61 to the side walls of the register. This cover plate is provided at its rear end with a transverse bar 62 in which is slidably 35 mounted a series of pins 63 which are pressed upwardly by means of springs 64 mounted between the heads of the pins and the bar 62.

As shown in the drawings, the bar 62 40 contacts with an arm 65 carried by the upper end of a spindle 66 which is slidably mounted in a transverse bar 67 suitably secured to the side walls of the register casing. A spring 68 is interposed between the 45 arm 65 and the transverse bar 67 and normally presses the arm 65 upwardly, the spindle 66 being provided with a pin 69 to limit its upward movement. The front portion 70 of the rear hinged wall 54 contacts 50 with the pins 63 as it is thrown into its closed position, forcing these pins downwardly thereby forcing the feeding rollers into contact with each other. However, before the rear wall 54 can be thrown into its 55 closed position the operator must press downwardly on the rear portion of the cover plate 60 in order to force the transverse bar 62 downwardly against the pressure of the springs 68 carried by the spindles 66. 60 Therefore, it will be seen that a positive and complete closing of the casing and inter-engagement of the feeding rollers is necessitated before the paper feeding mechanism is in operative position, the spring 68 being 65 sufficiently strong to hold the feeding rollers

out of engagement with each other and out of cooperative relation with each other until manual pressure is exerted to force these rollers into coactive relation.

The operation of the construction 70 described has been explained in connection with the details of construction and a further statement of the operation appears to be unnecessary.

From the foregoing specification it will 75 be seen that simple and effective means has been provided for insuring the proper adjustment of the paper feeding mechanism and that any feeding by secondary paper feeding mechanism, such as the feeding 80 means for the printing mechanism when the main feed is out of proper adjustment, has been prevented.

While we have in the above specification 85 described one embodiment of our invention, it should be understood that it is not our intention to limit ourselves to the specific construction described, but that further embodiments may be employed without departing 90 from the spirit and scope of the invention as expressed by the following claims.

Having thus described our invention, what we claim and desire to secure by Letters Patent is:

1. In a machine of the class described, 95 an autographic register, coacting paper feeding members, means for forcing one of said members away from the other member and out of operative engagement therewith and means including a movable casing member 100 for locking said members in operative engagement with each other.

2. In an autographic register, a casing, a cover plate therefor, coacting paper feeding 105 members carried by said casing and cover plate, means for holding said members out of operative engagement with each other, and locking means for locking said members in operative engagement with each other.

3. In a machine of the class described, an autographic register, paper feeding members carried thereby, resilient means for forcing said members out of operative engagement 110 with each other, means for locking said members in operative engagement with each other.

4. In a machine of the class described, an autographic register, feeding mechanism carried by said register, means including a hinged member for locking said feeding mechanism in operative adjustment, and means controlled by said member for preventing the operation of said feeding mechanism when said mechanism is out of proper adjustment.

5. In a machine of the class described, an autographic register, paper feeding mechanism carried thereby, supplemental feeding mechanism, actuating means for said supplemental feeding mechanism, means for hold-

- ing said first named mechanism in operative adjustment, and means controlled by said holding means for rendering said actuating means ineffective for driving a portion of said feeding mechanism. 85
6. In a machine of the class described, an autographic register having a platen, positively actuated paper feeding mechanism for feeding paper across said platen, actuating 10 means therefor, a hinged wall for said register, and means separate from and controlled by said hinged wall for rendering said actuating means ineffective to actuate said feeding mechanism. 40
- 15 7. In a machine of the class described, an autographic register, a casing for said register having a platen having a hinged wall, positively actuated paper feeding mechanism for feeding the paper across said 20 platen, operative connections for said paper feeding mechanism, and means separate from and controlled by said hinged wall for rendering said operative connections inoperative. 45
- 25 8. In a machine of the class described, an autographic register, paper feeding mechanism carried thereby, means including a hinged wall for holding said paper feeding mechanism in operative adjustment, supplemental feeding mechanism carried by said 50
- register, actuating means for said supplemental feeding mechanism, and means controlled by said hinged wall for rendering said actuating means ineffective to actuate the supplemental feeding mechanism. 55
9. In a machine of the class described, an autographic register, paper feeding mechanism carried thereby, means including a hinged wall for holding said paper feeding mechanism in operative adjustment, supplemental paper feeding mechanism, actuating means for said feeding mechanisms, operative connections between said actuating mechanism and said supplemental paper feeding mechanism, and means for throwing said connections out of operative position when said hinged wall is open. 60
10. In an autographic register, a casing, a cover plate therefor, coating paper feeding members carried by said casing and said cover plate, means for holding said members out of operative engagement with each other and means for locking said cover plate to the casing and said members in operative engagement with each other. 65

In testimony whereof we affix our signatures.

HENRY M. CROUSE.
GEORGE G. NEWELL.
